UNITED STATES PATENT OFFICE

2,505,170

STEAM GENERATING APPARATUS

Isaac Burnstein, Buffalo, N. Y., and Louis Burnstein, St. Catherines, Ontario, Canada, assignors of twenty per cent to Frank Pitterman, Buffalo, N. Y.

Application October 28, 1947, Serial No. 782,644

6 Claims. (Cl. 219—38)

1

This invention relates to certain new and useful improvements in steam generators designed primarily for use in tailoring, laundering and like establishments.

It has for one of its objects to produce a generator of this character which is simple, compact and inexpensive in construction, which is efficient in operation, and which is so designed as to instantaneously build up a supply of steam for pressing or like operations.

Another object is to provide an electrically-heated steam generator which is continuous and automatic in operation and which employs a novel arrangement of spray heads and associated parts for effectually converting the water into steam.

Other features of the invention reside in the construction and arrangement of parts herein-after described and particularly pointed out in the appended claims.

In the accompanying drawings:

Figure 1 is a sectional side elevation of the steam generator embodying our invention. Figure 2 is a cross section thereof taken on line 2—2, Figure 1. Figure 3 is an enlarged sectional elevation of one of the spray jets and the adjoining baffle. Figure 4 is a sectional elevation of a modified form of the steam generator. Figure 5 is a cross-section thereof taken on line 5—5, Figure 4. Figure 6 is an enlarged fragmentary vertical section taken on line 6—6, Figure 5.

Similar characters of reference indicate corresponding parts throughout the several views.

Referring to the embodiment of our invention shown in Figures 1—3 inclusive, 10 indicates a horizontally-disposed, outer cylindrical shell or casing and 11 indicates an inner cylinder of copper or like high, heat-conductive material disposed co-axially thereof and in spaced concentric relation thereto to provide an annular heating chamber 12. This chamber is closed at its ends by ring-like covers 13 while the inner cylinder 11, which constitutes a boiler or steam-generating chamber 14, is closed and sealed at its ends by inner and outer heads 15 and 16, respectively, bolted or otherwise secured to the ring-covers. Disposed within the heating chamber and coiled about the cylinder 11 are a plurality of electric heating coils or units 17 which are connected in parallel to the domestic current supply and which serve to heat such cylinder to a high temperature.

The inner head 15 has a sleeve or fitting 18 secured centrally thereof and connected to its outer end is a water feed pipe 19 having a check valve 20 and a hand-operated control valve 21

interposed therein. Projecting into the steam-generating chamber 14 and connected at their inner ends to this fitting are a plurality of jet pipes 22 each having a spray head or nozzle 23 connected thereto and extending in a generally radial direction to direct the spray against the inner wall of the cylinder 11. An angular shaped baffle or deflector 24 extends lengthwise of the cylinder in opposing relation to the wall thereof and in correlation to the nozzles to confine the spray within a given zone or area.

The outer head 16 is provided centrally thereof with a steam outlet pipe 25 for delivering the steam generated in the chamber 14 to a pressing machine or like apparatus. Interposed in this pipe is a safety valve 26 and a pressure gage 27. This head also has an auxiliary steam outlet 28 therein which is connected by a pipe 29 to a water pressure boosting device 30 having a water inlet pipe 31 leading thereto and a combined water and steam outlet pipe 32 leading therefrom and connected to the water feed pipe 19 at a point in advance of the valve 21. After the apparatus is started and steam pressure is built up in the chamber 14 some of this steam is utilized to inject the water at a greater pressure to the nozzles 23 to thereby create a fine spray or mist which, upon striking the hot cylinder wall, will be instantaneously converted to steam.

30 In the modification of our invention shown in Figures 4—6 inclusive, the generator is disposed in an upright position with the main parts thereof bearing the same reference characters as in the previous construction. The numeral 33 indicates a plurality of axially-disposed jet pipes connected at their lower ends to the fitting 18, while their upper ends have spray heads or nozzles 34 connected thereto and extending radially therefrom in equi-spaced relation for directing 35 the spray against the walls of the cylinder 11. Associated with each nozzle is a deflector or baffle 36 in opposing relation to the cylinder wall.

While manifestly simple, compact and inexpensive in construction, this steam generator is reliable and efficient in operation, it generates the steam instantaneously and assures an ample and continuous supply for use with pressing and like machines, and it requires a minimum of power to operate it. Furthermore, this apparatus may be used for heating purposes and the steam outlet thereof connected to radiators.

We claim as our invention:

1. A steam generator, comprising inner and outer cylinders disposed in concentric relation to provide an annular heating chamber and a

steam generating chamber having a water inlet and a steam outlet, means in operative relation to the walls of said inner cylinder for heating the same, and means in said generating chamber and in communication with said water inlet for directing sprays of water against the heated walls of the inner cylinder.

2. A steam generator, comprising inner and outer cylinders disposed in concentric relation and closed at their ends to provide an annular heating chamber and a steam generating chamber having a water inlet and a steam outlet, said inner cylinder being made of a high, heat-conducting material, an electric heating element coiled about the inner cylinder to heat the walls thereof, and nozzles in said generating chamber and in communication with said water inlet for directing sprays of water against the heated walls of said inner cylinder.

3. A steam generator, comprising inner and outer cylinders disposed in concentric relation to provide an annular heating chamber and a steam generating chamber having a water inlet and a steam outlet, means in operative relation to the walls of said inner cylinder for heating the same, and means including nozzle and baffle means disposed substantially centrally of and for directing sprays of water against the heated walls of the inner cylinder.

4. A steam generator, comprising inner and outer cylinders disposed in concentric relation and closed at their ends to provide an annular heating chamber and a steam generating chamber having a water inlet and a steam outlet, said inner cylinders being made of a high, heat-conducting material, an electric heating element coiled about the inner cylinder to heat the walls thereof, nozzles in said generating chamber and in communication with said water inlet for directing sprays of water against the heated walls of said inner cylinder, and baffle means in correlation to said nozzles and in opposing relation to the inner cylinder walls.

5. A steam generator, comprising inner and outer cylinders disposed in concentric relation to provide an annular heating chamber and a steam generating chamber having a water inlet and a steam outlet, means in operative relation to the walls of said inner cylinder for heating the same, means in said generating chamber and in communication with said water inlet for directing sprays of water against the heated walls of the inner cylinder, the latter having an auxiliary steam outlet therein, and an operative connection between said auxiliary steam outlet and said water inlet for injecting steam into the same for boosting the pressure of the water to the spray means.

10 6. A steam generator comprising a brass cylinder, an electric resistance heating coil on the exterior wall of the cylinder, means insulating the coil from said cylinder, plates closing the ends 15 of the cylinder, a distributor for water secured to one of the plates, a water supply connected to the distributor, a baffle having one end attached to the first-mentioned plate and projecting longitudinally through the cylinder, nozzles carried by the baffle, pipes connecting the nozzles with the distributor, said nozzles, pipes, baffle, distributor and first-mentioned plate being removable as a unit from the cylinder and means supplying an electric current to the heating coil.
